FELLING MACHINE FOR SEAMING FABRIC
SECTIONSCharles S. Thompson, Elmhurst, Ill., assignor to
Union Special Machine Company, Chicago, Ill.,
a corporation of Illinois

Application September 19, 1932, Serial No. 633,898

10 Claims. (Cl. 112—235)

The invention relates to new and useful improvements in sewing machines, and more particularly to a felling machine for joining the edges of fabric sections.

5 An object of the invention is to provide a machine of the above type with a feeding means and cooperating presser member which are so constructed as to grip the fabric sections at each side of the felled seam for the feeding of the

10 same.

A further object of the invention is to provide a machine of the above type wherein the presser member has a channel in its underface substantially the same width as the felled seam and of 15 a depth slightly greater than the thickness of the interfolded fabric sections so that the folded parts are relieved from excessive pressure and the fabric sections are fed to and from the stitching mechanism through the independent gripping of 20 said fabric sections alongside of and adjacent the felled seam.

A still further object of the invention is to provide a machine of the above type, wherein the presser member includes two fabric engaging sections arranged in tandem and wherein each fabric 25 engaging section is provided with a channel dimensioned so as to permit the free feed of the interfolded fabric sections through said channels.

These and other objects will in part be obvious 30 and will in part be hereinafter more fully disclosed.

In the drawings which show by way of illustration one embodiment of the invention,

Fig. 1 is a view showing a portion of a sewing 35 machine with the improvements applied thereto, the feeding means and the presser foot means being shown in side elevation.

Fig. 2 is a view partly in vertical section, and 40 partly in elevation from the rear of the presser foot.

Fig. 3 is a sectional view on the line 3—3 of Fig. 41.

Fig. 3a is a sectional view on the line 3a—3a which is through the front section of the presser 45 foot and the parts directly beneath the same.

Fig. 4 is a sectional view on the line 4—4 of Fig. 1.

Fig. 5 is a bottom plan view of the presser 50 foot.

Fig. 6 is a vertical sectional view through the presser foot and the feed dog.

Fig. 7 is a plan view of the feed dog.

Fig. 8 is a perspective view of the throat plate.

55 Fig. 9 is a perspective view showing two fabric

sections joined by a felled seam and with a cross felled seam therein.

The invention is directed to a machine for joining the edges of fabric sections by a felled seam. It includes a folder for overfolding the edge portion of one fabric section and the underfolding of the edge portion of another fabric section and the interfolding of the two fabric sections.

The stitching mechanism as illustrated includes 10 three needles and a looper which cooperates with each needle for forming independent lines of stitching. The material is fed across the work support by feeding means which includes a feed dog having feeding sections disposed so as to engage the fabric sections at each side of the felled seam and closely adjacent thereto. Cooperating with the feed dog is a presser foot which as shown is provided with two fabric engaging sections 15 arranged in tandem. These fabric engaging sections are pivotally mounted so that they may tilt independently and also so that one section 20 may be raised or lowered without disturbing the other section.

Each presser foot section is provided with a 25 channel in its underface which is of a slightly greater width than the felled seam and which is of slightly greater depth than the interfolded sections of fabric forming the felled seam.

It is thought the invention will be better understood by a detailed description of the illustrated embodiment thereof. The sewing machine includes a supporting base 1, carrying a standard 2, having an overhanging portion carrying a housing 3. Located in this housing is the main actuating shaft driven by a belt wheel indicated at 4. The housing 3 carries a needle head 5 in which a needle bar 6 reciprocates. The needle bar carries three needles 7, 8 and 9.

Suspended from the housing 3, is a work supporting arm 10 in which is located the compli- 40 mental stitch forming mechanism. There are three loopers, one for each needle. The looper 11 cooperates with the needle 7. These loopers are carried by a shaft 12 which is operated in the usual way. The machine shown is of the type illustrated in the patent granted N. V. Christensen and H. J. LeVesconte, December 24, 1929, No. 1,741,095, and further description thereof is 45 not thought necessary.

The material is fed off the work supporting arm by a feed dog 13, which is given four motions by suitable mechanism in the work arm 10. The machine is particularly adapted for joining the 50 edge portions of tubular garments and the fabric 55

sections to form the tube are placed around the arm and led into a folder 14. This folder is of the usual type for forming a felled seam. It overturns the lower fabric section and under-
 5 turns the upper fabric section and interfolds these portions so that when the fabric sections pass from the folder, they will be interfolded and ready for stitching. The fabric sections are led directly beneath the presser foot and to the stitching mechanism. The fabric sections are fed along the work support by the feed dog 13. This feed dog is shown in plan in Fig. 7. It includes the toothed section 15 and a toothed section 16. The feed dog also includes toothed sections 17 which engage the interfolded portions of the fabric sections directly in front of the needles. The feed dog also includes fabric engaging sections 18 which engage the interfolded sections directly in rear of the needles.

20 Mounted on the work supporting arm 10 is a throat plate 19, which has a feed slot 20, through which the section 15 of the feed dog operates, and a slot 21 through which a section 16 of the feed dog operates. There are also slots 22, 22 through 25 which the sections 17 and 18 operate. The throat plate is also provided with sections in which there are needle holes 7a, 8a and 9a for the needles 7, 8 and 9 respectively.

In Fig. 9 of the drawings, two fabric sections 30 are shown joined by a felled seam such as is made on the present machine. When these sections were joined on this machine, they were fed in the direction of the arrow in this figure so that the section F passed into the machine at the right of the path of the needles, while the section F' passed into the machine at the left of the path of the needles. The section F is underfolded as indicated at f, while the section F' is overfolded as indicated at f'. These folded parts are inter-
 35 folded and are joined by three lines of stitching indicated at a, b, c. The lines of stitching a, b, and c are made by the needles 7, 8 and 9, respectively. There is a cross felled seam F2, which was previously formed in each fabric section.

40 The material is held on the work support by a presser foot which, as illustrated, includes two presser foot sections arranged in tandem. The front presser foot section is indicated at 23 and the rear presser foot section is indicated at 24. The presser foot sections are carried by a lever 25. The lever 25 is connected to two spaced yoke arms 25a, 25a carried by a sleeve 26, which is attached to the lower end of the presser bar 27. The yoke arms 25a, 25a are spaced and the lever lies between the yoke arms and is connected thereto by pivot pins 28, 28, which are in alignment so that the lever 25 turns about the center of these pivots 28. The lever carries two spaced arms 29, 29, which project forward from the 45 pivotal connection 28. The presser foot section 23 has upstanding lugs 30, 30, which are pivoted to the arms 29, 29, by pivot pins 31, 31. These pivot pins are in alignment and the section 23 of the presser foot is adapted to tilt about the center 50 of the pivot pins 31 as an axis.

The lever 25 has a shank portion 32 in rear of the pivot centers 28 and the rear section 24 of the presser foot is pivotally connected to this shank. The presser foot has two upstanding lugs 33, 33, which are spaced so that the shank extends between the lugs, and a pivot rod 34, extending through the lugs and the shank connects the presser foot section 24 to the shank so that it is free to tilt on said pivot. The presser foot section 24 has an upturned toe 35. A spring 36 bears

on said upturned toe and is secured to the shank 32 by clamping screw 37. When the presser foot is unrestrained it will be turned in a clockwise direction by this spring 36 and the extent of movement of the foot section is limited by the rear portion contacting with the shank 32.

5 The lever 25 carries a rectangular boss 37 at the rear end thereof, which is located between guide bars 38 and 39, carried by the needle head. This permits the lever 25 to freely move up and down or to swing on its pivotal support but guides the same so as to prevent any lateral movement of the lever and the foot sections carried thereby.

A spring 40 is attached to the lever 25 at 41 and 15 to the sleeve 26 at 42. This spring tends to turn the lever 25 in a clockwise direction and the extent of movement is limited by the shank 32 contacting with the yoke arms 25a.

20 The section 23 of the presser foot is provided with openings 43, 43, one for each needle, said section also has an upturned toe portion 44. On the underface of the presser foot section 23, is a channel which is of substantially the same width as the felled seam or the interfolded portions of 25 the fabric sections. It is of a depth slightly greater than the thickness of the interfolded fabric sections. This channel in the presser foot provides guide walls 45, 45, which direct the felled seam. The portion 46 of the presser foot is directly above the feeding section 16 of the feed dog and the portion of the throat plate surrounding the same. The portion 47 of the presser foot is directly above the section 15 of the feed dog and the parts of the throat plate surrounding the 35 same. The section 46 bears on the fabric section F' adjacent the interfolded parts forming the felled seam. The portion 47 of the presser foot bears on the fabric section F, bending the same downward onto the throat plate and the 40 feed section. The wall 45 of the presser foot at the right as viewed in Fig. 3a, is placed a slightly greater distance from the center of the channel and the needle slots in order that the fabric sections may be folded down so as to be gripped 45 by the feed dog. The wall 45 of the presser foot at the other side of the channel is much closer to the needle slot at the stitching point and contacts with the fold in the fabric section F. This centers the interfolded parts and directs the same 50 to the stitching mechanism so that the needles will penetrate the interfolded parts in proper relation to the folds in the fabric sections.

55 The channel extends up the toe and the side 48 thereof is extended to aid in the guiding of the 55 fabric sections beneath the foot. This part of the presser foot contacts with the fold in the fabric section F. The section 24 of the presser foot is also provided with a channel in its underface. This channel is of slightly greater width than the 60 felled seam and in addition thereto the thickness of the fabric section which is bent downward and is also of greater depth than the thickness of the interfolded fabric sections. In other words, it is of considerably larger dimensions 65 than the channel in the forward section of the presser foot and is so dimensioned in order to give ample clearance for the passing of the felled cross seam, such as indicated at F2 in Fig. 9. The presser foot section 23 has a rearwardly projecting portion 49 which extends into the channel in the foot section 24.

70 The channel in the rear section 24 of the presser foot is indicated at 50. The side walls of the channel are inclined so as to give greater free- 75

dom of movement for the cross seam. Alongside of the channel is a section 46a, corresponding to the section 46 and operating in similar manner thereto in conjunction with the feeding means. 5 There is likewise a section 47a at the other side of this channel 50, which operates in a manner similar to the section 47 on the front presser foot.

The channel in the forward section of the presser foot is of sufficient depth so that there 10 is very little pressure on the interfolded sections of the fabric. Inasmuch as the fabric sections are not compacted, the needles will more readily penetrate the same and the felled seam will pass more freely through the channel. The side portions 15 of the presser foot operate independently on the fabric sections firmly clamping the same against the throat plate or the feed dog. Thus it is that the fabric sections are fed through the folder and beneath the presser foot to the stitching 20 mechanism.

When a cross seam passes beneath the presser foot section 23, it will tilt and the rear end of the foot will engage the fabric in rear of the cross seam until it reaches the needles or passes 25 the pivotal center 31, after which the forward portion of the presser foot engages the fabric sections in front of the cross seam. The cross seam will also cause the rear section 24 of the presser foot to tilt as it passes underneath the 30 same. The front section may rise independently of the rear section so that when the front section is raised by the cross seam, the rear sections 46a and 47a are firmly holding the fabric sections pressed in contact with the feed dog. When the 35 rear section of the presser foot is raised by the cross seam, the forward section of the presser foot will bear on the fabric, firmly holding the same in contact with the feed dog. This is accomplished by the pivoting of the lever 25 which carries the presser foot sections. The channel in the 40 rear section of the presser foot is made of sufficient dimension so as to permit a cross seam to freely pass through the same.

By the forming of the front section of the 45 presser foot with a channel so dimensioned as to relieve the interfolded sections of the fabric from excessive pressure, the stitches can be set deeper into the material. The roof of the channel, however, is sufficiently close to the fabric sections as to 50 restrain the upward movement of the needles and insure the proper formation of the needle loops and thus prevent the skipping of stitches. By 55 this construction of presser foot, wherein there is a freedom of movement of the interfolded fabric sections, the strain and wear on the moving parts of the machine is greatly reduced.

While there is shown a presser foot formed in two sections arranged in tandem, it will be understood that from certain aspects of the invention 60 a single presser foot may be used, dimensioned so as to give freedom of movement to the interfolded portions of the fabric sections and so as to firmly clamp the fabric sections against the feed dog or the throat plate, so that they are under 65 perfect control during the feed cycle.

It is obvious that minor changes in the details of construction and the arrangement of parts 70 may be made without departing from the spirit of the invention as set forth in the appended claims.

Having thus fully described the invention, what I claim as new and desire to secure by Letters Patent is:

1. In a sewing machine the combination of a 75 work support, means for interfolding fabric sec-

tions to form a felled seam, stitching devices for uniting the interfolded fabric sections, feeding means and a presser member cooperating with said feeding means, said presser member having a channel extending longitudinally therethrough of a depth slightly greater than the thickness of the interfolded fabric sections guided thereby, whereby said interfolded sections are free from restraining members contacting therewith, said feeding means and cooperating presser member 10 being constructed so that the fabric sections are gripped alongside of and adjacent the interfolded parts for the feeding of the same.

2. In a sewing machine, the combination of a work support, means for interfolding fabric sections to form a felled seam, stitching devices for uniting the interfolded fabric sections, feeding means, a presser member cooperating with said feeding means in the region of the stitching devices, said presser member having a channel extending longitudinally therethrough and of a depth slightly greater than the thickness of the interfolded fabric sections guided thereby, said feeding means and cooperating presser member 15 being constructed so that the fabric sections are gripped along side of and adjacent the interfolded parts for the feeding of the same, and a presser member located in rear of the first-named presser member and cooperating with said feeding mechanism to aid in the feeding of the fabric sections. 20

3. In a sewing machine the combination of a work support, means for interfolding fabric sections to form a felled seam, stitching devices for uniting the interfolded fabric sections, feeding means and a presser member cooperating with said feeding means, said cooperating presser member having a channel in its underface providing a free and unobstructed passage dimensioned so as to permit the free movement of the interfolded sections through the channel and so as to provide a fabric engaging section at each side of said channel cooperating with the feeding means for normally clamping the fabric sections only alongside and adjacent the interfolded portions of the fabric sections for the feeding of the same. 30

4. In a sewing machine the combination of a work support, means for interfolding fabric sections to form a felled seam, stitching devices for uniting the interfolded fabric sections, feeding means and a presser member cooperating with said feeding means, said presser member including 40 presser foot sections arranged in tandem and cooperating with the feeding means, each presser foot section having a channel in its underface dimensioned so as to guide the interfolded portions of the fabric sections and permit free movement of the same through the channel. 45

5. In a sewing machine the combination of a work support, means for interfolding fabric sections to form a felled seam, stitching devices for 50 uniting the interfolded fabric sections, feeding means and a presser member cooperating with said feeding means, said presser member including presser foot sections arranged in tandem and means for supporting said presser foot sections 55 whereby each section may tilt independently about an axis at right angles to the feed and whereby the presser foot sections may have independent vertical movements, each of said presser foot sections having a channel in the underface 60 thereof extending from the front of the presser member to the rear thereof, which channels are dimensioned so as to permit the free movement of the interfolded portions of the fabric sections. 65

6. In a sewing machine the combination of a 70

work support, means for interfolding fabric sections to form a felled seam, stitching devices for uniting the interfolded fabric sections, feeding means and a presser member cooperating with said feeding means, said presser member including presser foot sections arranged in tandem and cooperating with the feeding means, each presser foot section having a channel in its underface dimensioned so as to guide the interfolded portions 10 of the fabric sections and permit free movement of the same through the channel, each presser foot section having a fabric engaging portion at each side of the channel therein adapted to cooperate with a feeding means for clamping the 15 fabric sections and feeding the same.

7. In a sewing machine the combination of a work support, means for interfolding fabric sections to form a felled seam, stitching devices for uniting the interfolded fabric sections, feeding 20 means and a presser member cooperating with said feeding means, said presser member including presser foot sections arranged in tandem and means for supporting said presser foot sections whereby each section may tilt independently about 25 an axis at right angles to the feed and whereby the presser foot sections may have independent vertical movements, each of said presser foot sections having a channel in the underface thereof extending from the front of the presser member to 30 the rear thereof, which channels are dimensioned so as to permit the free movement of the interfolded portions of the fabric sections, each presser foot section having a fabric engaging portion at each side of the channel therein adapted to cooperate with a feeding means for clamping the 35 fabric sections and feeding the same.

8. In a sewing machine the combination of a work support, means for interfolding fabric sections to form a felled seam, stitching devices for 40 uniting the interfolded fabric sections, feeding means and a presser member cooperating with said feeding means, said presser member including presser foot sections arranged in tandem, means for supporting said presser foot sections 45 so that each section may tilt independently of the other about an axis at right angles to the line of feed, yielding means cooperating with the rear presser foot section for depressing the forward end thereof, said means for supporting said 50 presser foot sections being pivotally and yieldingly supported intermediate said sections and yielding means associated with said supporting

means for yieldingly moving said front section into contact with the material.

9. In a sewing machine the combination of a work support, means for interfolding fabric sections to form a felled seam, stitching devices for 5 uniting the interfolded fabric sections, feeding means and a presser member cooperating with said feeding means, said presser member including presser foot sections arranged in tandem, means for supporting said presser foot sections so 10 that each section may tilt independently of the other about an axis at right angles to the line of feed, yielding means cooperating with the rear presser foot section for depressing the forward end thereof, said means for supporting said 15 presser foot sections being pivotally and yieldingly supported intermediate said sections and yielding means associated with said supporting means for 20 yieldingly moving said front section into contact with the material, each presser foot section having a channel in its underface of slightly greater width than the felled seam and of greater depth than the thicknesses of the fabric sections forming the same.

10. In a sewing machine the combination of a work support, means for interfolding fabric sections to form a felled seam, stitching devices for uniting the interfolded fabric sections, feeding means and a presser member cooperating with said feeding means, said presser member including 25 presser foot sections arranged in tandem, means for supporting said presser foot sections so that each section may tilt independently of the other about an axis at right angles to the line of feed, yielding means cooperating with the rear presser 30 foot section for depressing the forward end thereof, said means for supporting said presser foot sections being pivotally and yieldingly supported intermediate said sections and yielding means associated with said supporting means for 35 yieldingly moving said front section into contact with the material, each presser foot section having a channel in its underface of slightly greater width than the felled seam and of greater depth than the thicknesses of the fabric sections forming the same, each presser foot section having fabric engaging portions at the sides of the channels therein cooperating with the feeding means 40 for clamping the fabric sections for feeding the same.

CHARLES S. THOMPSON.
